FALSE FACE

George L. Edwards, Fuquay Springs, N. C.

Application March 7, 1938, Serial No. 194,475

1 Claim. (Cl. 2—206)

This invention relates to devices commonly known as false faces, the primary object of the invention being to provide a false face constructed in such a manner that it may be readily inflated or deflated by the person wearing the false face, thereby changing the contour of the false face to the amusement of persons observing the wearer of the false face.

An important object of the invention is the provision of a false face of this character constructed of rubber material and formed with air pockets which may be inflated at the will of the user, deforming the contour of the face causing the false face to take irregular and abnormal lines, rendering the false face exceptionally hideous or comical.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

In the drawings:

Figure 1 is an elevational view, illustrating the false face as positioned over the face of the wearer.

Figure 2 is a side elevational view thereof, portions of the false face being shown in section to illustrate the air pockets, and tube by means of which the air pockets are inflated.

Figure 3 is a segmental sectional view illustrating the construction of the false face at the nostrils of the wearer and taken on line 3—3 of Figure 1.

Figure 4 is a longitudinal sectional view through the inflating tube, illustrating the movable section of the tube as moved forwardly so that air may pass into the body portion of the false face.

Figure 5 is an elevational view of the inflating tube, the forward portion of the inflating tube being illustrated in section, showing the position of the movable section of the inflating tube, preventing deflation of the body portion of the false face.

Referring to the drawings in detail, the false face is constructed of two sheets of rubber material of an exceptionally thin grade. The outer section of the body portion is indicated by the reference character 5, while the inner section thereof is indicated by the reference character

6 and in the construction of the false face, portions of these sections are vulcanized together, at various places throughout the contacting surfaces thereof, as at 7, portions of the adjacent surfaces of the strip being disengaged providing spaces or pouches such as indicated at 8, falling opposite the cheeks of the wearer, and the space or pouch 9, disposed directly opposite to the nose of the wearer. Ear pouches indicated by the reference character 10, communicate with the spaces or pouches 8, through the passageways 11, whereby air entering the spaces or pouches 8, may pass into the ear pouches 10 to inflate them.

A passageway indicated by the reference character 12 establishes communication between the compartment 13 and the space or pouch 9, so that air may pass into the pouch or space 9 inflating the same. Lateral passageways indicated by the reference character 14 establish communication between the compartment 13 and spaces or pouches 8 at the cheeks of the wearer.

The reference character 15 designates the inflating tube of the false face, and as shown this inflating tube extends into the compartment 13. This inflating tube is of a length so that it may be extended into the mouth of the wearer of the false face, and gripped between his teeth, in holding the tube while the false face is being inflated.

Mounted for sliding movement within the tube 15, is a tube indicated at 16. This tube 16 is of a length greater than the length of the tube 15 and is provided with enlargements 17 at its ends, so that movement of the tube 16 longitudinally of the tube 15 will be restricted in either direction.

Formed in the outer end of the tube 16, are openings indicated at 18, which openings, when the tube 16 is moved to a position as illustrated by Fig. 4 of the drawings, permit air to pass from the tube 16, into the compartment 13 and various passageways and spaces or compartments of the false face, inflating the spaces or pouches to the desired degree.

It is obvious that when the person wearing the false face, forces the tube 16 outwardly to the position shown by Figure 4, and when the false face has been properly inflated, the tube 16 will, when pressure by the tongue of the person wearing the false face, is released at the inner ends of the tube 16, air pressure in the various spaces or compartments of the false face, will contact with the outer closed end 18 of the tube 15, forcing the tube to the position as illustrated by Fig. 5 of the drawings, thereby prevent-

ing air from passing from the spaces or pouches of the false face to deflate the false face.

Should the operator desire to deflate the false face, it is only necessary to press the tongue against the inner end of the tube 16, moving the tube forwardly exposing the opening 18, whereby air may pass into the tube 16 from the compartment 13, and exhaust into the mouth of the wearer of the false face.

10 In order that the false face may be conveniently worn on the head of a person, securing straps indicated by the reference character 20 are provided, the straps being of length to pass around the rear surface of the head and neck of the 15 wearer. The lowermost strap 20 is shown as formed with a head 21 adapted to be passed through the ring 22, removably securing the lower strap in position to facilitate the positioning and removal of the false face.

20 To further secure the false face in position on the head of the wearer, the rubber ear members 23 are provided, and are in the form of loops, adapted to be stretched over the ears of the wearer.

In view of the foregoing description, it is believed that a further detailed description as to the use of the device is unnecessary.

What is claimed is:

5 In a false face, a body portion including outer and inner contacting walls constructed of flexible material and secured together at predetermined points, portions of the walls between the secured portions thereof providing pouches, passageways connecting the pouches, a valve including a main valve tube connected with the body portion, an inner valve tube mounted within the main valve tube and slideable longitudinally thereof, one end of the inner valve tube being closed, said inner valve tube having openings 10 formed in the wall thereof and through which air passes to said pouches, said valve tube being normally moved to its closed position by air pressure within the false face, and said valve tube adapted to be moved to a position to admit 15 air to the pouches, by the tongue of the person using the false face.

GEORGE L. EDWARDS.
